(57) **CLAIM**

The ornamental design for a hand-held power tool and a display on a hand-held power tool, as shown and described.

DESCRIPTION

FIG. 1 is a right side elevation view of the tool in accordance with a first embodiment;

FIG. 2 is a front elevation view of the tool of FIG. 1;

FIG. 3 is a left side elevation view of the tool of FIG. 1;

FIG. 4 is a rear elevation view of the tool of FIG. 1;

FIG. 5 is a top plan view of the tool of FIG. 1;

FIG. 6 is a bottom plan view of the tool of FIG. 1;

FIG. 7 is a perspective view of the tool of FIG. 1;

FIG. 8 is a front elevation view of the display on the tool of the first embodiment;

FIG. 9 is a right side elevation view of the tool in accordance with a second embodiment;

FIG. 10 is a front elevation view of the tool of FIG. 9;

FIG. 11 is a left side elevation view of the tool of FIG. 9;

FIG. 12 is a rear elevation view of the tool of FIG. 9;

FIG. 13 is a top plan view of the tool of FIG. 9;

FIG. 14 is a bottom plan view of the tool of FIG. 9; and,

FIG. 15 is a perspective view of the tool of FIG. 9.

The elements shown in broken line in the drawings is for the purpose of showing environmental structure and forms no part of the claimed design.

1 Claim, 15 Drawing Sheets
